UNITED STATES PATENT OFFICE.

HARVEY H. TROXEL, OF WOOSTER, OHIO, ASSIGNOR OF ONE-HALF TO JOHN J. KINNEY,
OF WOOSTER, OHIO.

SUPPLY-INDICATING DEVICE.

1,280,903.

Specification of Letters Patent.

Patented Oct. 8, 1918.

Application filed April 29, 1918. Serial No. 231,372.

To all whom it may concern:

Be it known that I, HARVEY H. TROXEL, a citizen of the United States, residing at Wooster, in the county of Wayne and 5 State of Ohio, have invented certain new and useful Improvements in Supply-Indicating Devices, of which the following is a specification.

My invention relates to improvements in 10 supply indicating devices, the present embodiment of the invention being particularly designed and adapted for use as a mail supply indicator by the patrons of rural free delivery mail routes, the improved indicator 15 being adapted to be placed in or upon the rural mail box and supplied with suitable means for indicating to the rural mail carrier the kind and amount of particular mail supplies desired, as well as providing a suitable 20 coin receptacle for holding the exact amount of money necessary to cover the entire order.

The primary object of the invention is to 25 provide a generally improved supply indicator of this class to be exceedingly simple in construction, cheap of manufacture, and efficient in use.

With the above mentioned and other ends 30 in view, the invention consists in the novel construction, arrangement, and combination of parts, hereinafter described, illustrated in one of the embodiments in the accompanying drawings, and particularly pointed out in the appended claims.

35 Referring to the drawings, forming a part of this specification, Figure 1, is a front view of the improved supply indicator, the indicator keys being removed and the blank for forming the coin receptacle at the rear and 40 at one end of the card or face member being open to show the form of the blank before being folded up.

Fig. 2, a front elevation of the same complete.

45 Fig. 3, a top or edge view of the same.

Similar numerals of reference designate like parts throughout all the figures of the drawings.

The improved indicator comprises a suitable 50 card or face member 1, provided at one side with a tabular list of various supplies, as at 1^a, as for example,—1¢-stamps, 2¢-stamps, post-cards, stamped envelops, and the like, and opposite each line in the list

of supplies a plurality of openings 1^b, are 55 arranged in horizontal alinement therewith. These openings 1^b, are also arranged in vertical lines or columns, and above this panel of openings a horizontal line of numerals is provided, said numerals being arranged in 60 vertical alinement with the openings 1^b, for indicating the number or quantity of the particular supplies desired, as for example,—the number of stamps, post-cards, 65 or envelops appearing in horizontal alinement with the indicator key, as hereinafter referred to.

As a means of conveniently indicating the supplies ordered, a plurality of indicator keys 2, are provided, said indicator keys, in 70 the present instance, being in the form of expansible interlocking key or indicator members, as for example, in the specific form of cotter pins, adapted to be inserted in the openings 1^b, and to interlock therewith when 75 in position, and as a means of holding the interlocking indicator keys in convenient position for use, as well as preventing their loss, such indicators may be flexibly connected to the card or face member 1, by means of a 80 plurality of flexible cable or cord members 3, of convenient length to readily cover the panel of perforations or openings 1^b. One end of the card or face member is cut into suitable blank form, as at 4, and is adapted 85 to be folded up along predetermined lines, as at 4^a, so as to fold up at the rear of the card or face member, and the one end thereof of forming a coin receptacle 5, the flap 4^b, forming the bottom of the receptacle when 90 folded. The free edges of the flaps forming the coin receptacle may be secured to the rear of the card or face member 1, in any suitable and convenient manner, as for example, by means of suitable fastening members 6, or, if desired, pasted thereon, in a 95 well known and obvious manner.

As indicated in the accompanying drawings, the first indicator key 2, at the top shows that ten 1¢-stamps are wanted, the 100 second indicator key, opposite the 3¢-stamp column and below the numeral 5, indicates that five 3¢-stamps are desired, and the last indicator key at the bottom indicating that two 3¢-envelops are wanted, and the rural 105 carrier will therefore expect to find 31¢ in change in the coin receptacle 5.

From the foregoing description, taken in

connection with the accompanying drawings, the operation and advantages of my invention will be readily understood.

Having thus described one of the embodiments of my invention, what I claim and desire to secure by Letters Patent, is,—

1. In an indicating device, a portable card member provided on its front with a tabular supply list and a plurality of openings and indicator numerals, and expansible interlocking indicator keys carried by certain of said openings of said card member removably connected to the latter.
- 10 2. In an indicating device, a portable card

member provided on its front with a vertical supply list and horizontal indicator numerals with a plurality of openings in horizontal and vertical alinement therewith, and interlocking indicator keys removably carried by certain of said openings of said card member.

In testimony whereof I have affixed my signature in the presence of two witnesses.

HARVEY H. TROXEL.
